(57) **CLAIM**

The ornamental design for a toothbrush handle, as shown and described.

DESCRIPTION

FIG. 1 is a perspective view of a toothbrush handle showing our new design;

FIG. 2 is a rear elevational view thereof;

FIG. 3 is a front elevational view thereof;

FIG. 4 is a left side elevational view thereof, the right side being a mirror image; and,

FIG. 5 is a bottom plan view of the toothbrush handle of FIG. 1.

The broken line showing of environment is for illustrative purposes only and forms no part of the claimed design.
